MANHOLE

Filed Oct. 14, 1927

UNITED STATES PATENT OFFICE

CLIFTON A. GLASS, OF KANSAS CITY, MISSOURI, ASSIGNOR TO KANSAS CITY STRUCTURAL STEEL COMPANY, OF KANSAS CITY, MISSOURI, A CORPORATION OF MISSOURI

MANHOLE

Application filed October 14, 1927. Serial No. 226,125.

My invention relates to manhole closures for oil or like tanks and more particularly to a structure of that character adapted for location in the side wall of a tank of large capacity where it is subjected to extreme pressures from contents of the tank; the principal object of the invention being to provide a gas and liquid tight closure, capable of withstanding extreme pressures, but 10 easily manipulatable to provide access to the tank.

In ordinary tank construction a ring and a cover plate are provided of cast iron or cast steel, and riveted at the factory to the 15 particular plate of the tank having the opening. A cast manhole assembly is relatively massive, both because of the requirement of strength to withstand pressure from a high head of oil in the tank and because of 20 the wide web and ring flanges necessary to provide the means for fastening the cover to the ring; and which, when attached to a tank plate, presents a troublesome problem in transportation. Cast iron covers and 25 frames moreover are more or less porous and likely to contain air holes, through which the oil or contents of the tank may leak and which may not be discovered until the tank is set up and supplied with oil. 30 The extreme penetrability of oil requires therefore that covers and frames be provided of dense solid material, to retain it. Rolled steel plate has been used for covers; and manhole frames have been built up of 35 two or more rolled steel members welded together, the latter structure presenting undesirable features of cost and bulk. It is to overcome these and other disadvantages 40 of such ordinary construction, and to provide an efficient manhole closing means, that the present invention was designed.

In accomplishing the above and other objects of the invention I have provided improved details of structure, the preferred 45 forms of which are illustrated in the accompanying drawings, wherein:

Fig. 1 is a perspective view of a portion of a tank including a manhole closure constructed in accordance with my invention.

Fig. 2 is a vertical section of such por-

tion of a tank, on a line running centrally through the manhole.

Fig. 3 is a sectional view on the lines 3—3, Fig. 1.

Referring in detail to the drawings: 55 1 designates the bottom of an oil storage tank, 2 a bottom flange and 3 one of the plates riveted to the bottom flange to constitute the first course or ring of the tank structure. A plate or sheet comprising part 60 of the shell is illustrated for convenience but the plate 3 may be considered a flat plate in a side, top or bottom wall of a container or partition, having a manhole opening 4 for the closure of which the present 65 invention, including the manhole elements designated generally 5, is designed.

The manhole closure comprises a ring 6 having an interior diameter corresponding to that of the manhole and having rivet 70 openings 7 for receiving rivets 8 whereby the ring is secured to the outer face of the plate 3 of the tank. 9 designates a cover of greater diameter than the interior diameter of the ring to overlie the ring when the 75 parts are assembled.

Attached to the inner face of the tank wall and surrounding the manhole opening is a reinforcing plate 10, having an interior diameter 11 greater than that of the opening 80 and substantially equal to the exterior diameter of the ring to provide an exposed wall portion to which the ring 6 may be directly riveted as shown in Figs. 2 and 3; the reinforcing member being secured to the tank 85 plate by rivets 12.

The ring 6 is preferably formed from rolled steel to comprise an exterior annular recessed portion or flange 13 through which the attaching rivets 8 are projected and an 90 outstanding annular rail 14 for seating the cover plate 9 and provided with threaded sockets 15 for receiving stud bolts 16; a gasket 17 being interposed between the cover plate and seat, and nuts 18 being provided 95 for the outer ends of the stud bolts for securing the cover in tight engagement with the ring.

I further provide as an important feature of ring structure, the beveled outer edge 19 100

on the flange 13, whereby the caulking of the flange into sealing engagement with the shell plate is facilitated. The fact that the integral ring member of my structure is formed of rolled steel provides for efficient caulking with no liability of such breakage as may result from similar battering of cast members.

The flange or recessed portion 13 is provided as described to permit the use of relatively short rivets 8 for securing the ring to the tank shell plate without sacrifice of tightness. Sufficient depth for the setting of the studs is provided by the portion 14 having normal thickness.

A closure like that described, while smaller and lighter than those of ordinary construction, is much less liable to breakage and is more effective for preventing leakage of gases and oils. It further provides a structure offering less opportunity for damaging contact by exterior objects and one which may be easily and quickly assembled and wherein the cover plate may be easily and quickly removed or replaced when access is to be had to the tank from the manhole.

What I claim and desire to secure by Letters Patent is:

1. In combination with a tank wall having a manhole, a reinforcing plate on the inner face of the wall having an opening concentric with but of greater diameter than the manhole, a ring attached to the outer face of the wall having its inner periphery registering with the manhole opening and having its outer periphery substantially registering with the inner periphery of the reinforcing plate, means for securing the ring to the tank, and a cover removably attached to the ring.

2. In combination with a tank wall having a manhole opening, a reinforcing plate attached to the inner face of the wall having an opening concentric with but of greater diameter than the manhole opening, a ring attached to the outer face of the wall about the manhole opening, including an inner body part provided with a cover seat having its inner periphery registering with the manhole opening, and an outer flange, means extending through the flange and through the tank wall interiorly of the reinforcing plate for attaching the ring to the wall, and a cover plate attached to the ring seat.

55 In testimony whereof I affix my signature.
CLIFTON A. GLASS.
